UNITED STATES PATENT OFFICE.

AXEL MARTIN LUNDSTROM, OF ERIE, PENNSYLVANIA.

BEDSPRING REENFORCEMENT.

Application filed January 18, 1922. Serial No. 530,203.

To all whom it may concern:

Be it known that I, AXEL M. LUNDSTROM, a subject of the King of Sweden, having declared my intention of becoming a citizen of the United States, and having received my first papers, residing at Erie, in the county of Erie and State of Pennsylvania, have invented new and useful Improvements in Bed-spring Reenforcements, of which the following is a specification.

This invention is designed to re-enforce bed springs, especially woven wire springs to prevent the sagging which ordinarily takes place in such springs.

15 The invention is illustrated in the accompanying drawings as follows:—

Fig. 1 shows a plan view of the re-enforcement.

Fig. 2 a central section through the device 20 and a bed.

1 marks the bed posts, 2 the rails of the bed, 3 a woven wire spring mounted on the bed, and 4 a mattress on the spring. These are of ordinary construction.

25 The spring re-enforcement comprises a flexible platform 5. This is made up of peripheral flat bars 6 united at the corners by rivets 7. Flat bars 8 extend diagonally from corner to corner, being secured at the 30 corners by the rivets 7.

A spring 9 engages the platform at the point of crossing of the bars 8. It is supported by a post 10 resting on a cross bar 11. The cross bar has the rail engaging 35 members 12 with the hooks 13 resting on the rails 2. The post 10 is preferably made up of the screw-threaded member 14 on which the spring 9 rests and a screw-threaded member 15 extending upwardly from the

40 cross bar and the threads on the members 14 and 15 being reversed and engaged by a turn buckle 16 by which the post may be expanded to adjust the spring 9.

In order to adjust the rail engaging members to different widths of beds the cross bar 11 is provided with the screw-threaded nuts 17 and the members 12 are screw-threaded at 18 so that they may be screwed into or out of the cross bar 11 to adjust them to 50 different widths of bed.

In order to yieldingly engage the peripheral portions of the platform I prefer to provide a flat metal spring 19 resting on the post 10 having the bends 20 at their outer edges and engaged to the peripheral bars 6 at 21, the bends 20 permitting of the yielding extension of the spring as it is deflected.

With this device, therefore, there is a yielding support which prevents the sagging of the bed of the woven wire type and can be readily applied to beds in use.

What I claim as new is:—

1. In a bed spring re-enforcement, the combination of a supporting bar; a flexible platform above the bar; and an adjustable spring connection between the bar and platform comprising a spring and an expanding post for adjusting the spring.

2. In a bed spring re-enforcement, the combination of a supporting bar; a flexible platform above the bar; and a spring connection between the bar and platform comprising springs supported at a centrally located point on the bar and engaging the platform centrally and peripherally.

3. In a bed spring re-enforcement, the combination of a supporting bar; a flexible platform above the bar; and a spring connection between the bar and platform comprising a coil spring engaging the platform centrally and a flat metal spring extending to the edges of the platform.

4. In a bed spring re-enforcement, the combination of a supporting bar; a flexible platform formed with a periphery of flat metal bars and cross bars; and a spring connection between the platform and the supporting bar engaging the cross bars.

5. In a bed spring re-enforcement, the combination of a supporting bar; a flexible platform formed with a periphery of flat metal bars and cross bars; and a spring connection between the platform and the supporting bar engaging the cross bars and the peripheral bars.

In testimony whereof I have hereunto set my hand.

AXEL MARTIN LUNDSTROM.
